AGENT

UNITED STATES PATENT OFFICE

167,911

KNITTING DEVICE OR SIMILAR ARTICLE

James Murray Smith, Denver, Colo.

Application May 8, 1952, Serial No. 19,634

Term of patent 14 years

(Cl. D47—5)

To all whom it may concern:

Be it known that I, James Murray Smith, a citizen of the United States, residing at Denver, in the county of Denver and State of Colorado, have invented a new, original, and ornamental Design for a Knitting Device or Similar Article, of which the following is a specification, reference being had to the accompanying drawings forming a part thereof.

Fig. 1 is a perspective view of a knitting device or similar article showing my new design;

Fig. 2 is a side elevational view thereof;

Fig. 3 is a front elevational view thereof.

I claim:

The ornamental design for a knitting device or similar article, substantially as shown.

JAMES MURRAY SMITH.
